UNITED STATES PATENT OFFICE.

BLANCHE STEVENS-ARVOY, NÉE RENEAUX, OF PARIS, FRANCE, AND JOSEPH A. FIELDS,
OF NEW YORK, N. Y.

DESIGN FOR A COMBINED PERFUME BOTTLE AND HOLDER.

Application filed December 12, 1924. Serial No. 11,683. Term of patent 14 years.

To all whom it may concern:

Be it known that BLANCHE STEVENS-ARVOY, née RENEAUX, citizen of the Republic of France, and residing in Paris, France, and JOSEPH A. FIELDS, citizen of the United States, and resident of the city of New York, in the county of New York and State of New York, have invented a new, original, and ornamental Design for Combined Perfume Bottle and Holder, of which the following is a specification, reference being had to the accompanying drawing, forming part thereof, in which—

The figure is a perspective view of a combined perfume bottle and holder embodying my new design, which is manufactured and sold as a single unitary article.

We claim:

The ornamental design for a combined perfume bottle and holder as shown.

Signed at Paris, France, November 10, 1924.

BLANCHE STEVENS-ARVOY, née RENEAUX.

Signed at New York city, October 2, 1924.

JOSEPH A. FIELDS.
